CLAIM

The ornamental design for a display device with stand, as shown and described.

DESCRIPTION

FIG. 1 is a perspective view of a display device with stand in accordance with the new design;

FIG. 2 is a front view of the display device with stand of FIG. 1;

FIG. 3 is a back view of the display device with stand of FIG. 1;

FIG. 4 is a right side view of the display device with stand of FIG. 1;

FIG. 5 is a left side view of the display device with stand of FIG. 1;

FIG. 6 is a top view of the display device with stand of FIG. 1;

FIG. 7 is a bottom view of the display device with stand of FIG. 1;

FIG. 8 is a perspective view of the display device with stand of FIG. 1;

FIG. 9 is a perspective of the display device with stand of FIG. 1; and,

FIG. 10 is a perspective view of the display device with stand of FIG. 1.

The broken lines in the drawings are directed to portions of the depicted display device with stand that form no part of the claimed design.
